CONTAINER FOR SHAVING CREAM, TOOTH PASTE, AND THE LIKE

Henry C. Everett, Jr., Boston, Mass., and Christopher L. Migliaccio, Cranston, R. I., assignors to Old Colony Distributing Company, Boston, Mass., a Corporation of Massachusetts

Application December 24, 1930
Serial No. 504,442

3 Claims. (Cl. 221—78)

This invention relates to containers for dispensing shaving cream, toothpaste, facial cream, and other preparations of a similar nature.

Preparations of this character are customarily sold in collapsible metal tubes which are thrown away when empty. It is sometimes desirable, however, to carry a quantity of material of this kind in a permanent container which may form a part of a shaving kit, toilet set, or the like, and it is the chief object of the present invention to devise such a container.

The fact that these substances exert a very corrosive action on the metals which would naturally be used in making such containers introduces very serious practical difficulties. Not only do such metals combine chemically with ingredients of the pastes and creams which make the latter unsuitable for use, but some of the compounds so produced are poisonous. The present invention deals especially with these conditions. It aims to devise a container for the purpose above mentioned which can be used with entire safety and which, at the same time, will be relatively inexpensive to manufacture.

The nature of the invention will be readily understood from the following description when read in connection with the accompanying drawing, and the novel features will be particularly pointed out in the appended claims.

30 In the drawing,

Figure 1 is a perspective view of a shaving kit which includes a container embodying features of this invention;

Fig. 2 is a side elevation of the container;

35 Fig. 3 is a vertical sectional view on a larger scale showing the internal construction of the container; and

Fig. 4 is a side view, partly broken away and partly in section, illustrating a convenient means 40 for withdrawing the plunger from the container.

The particular container shown in the drawing is designed to be used as one element of a shaving kit which includes a safety razor and a folding shaving brush, all enclosed in a casing

45 2. The container is illustrated at 3, the handle of the razor at 1, and the blade holder for the razor at 5.

Referring more particularly to Figs. 2 and 3, it will be seen that the container there shown 50 comprises a relatively rigid tubular shell which includes a body 3 and an end piece 4 soldered, brazed, swaged, or otherwise permanently secured to the body. This shell usually consists of some metal such as brass, bronze, or any of the various alloys from which commercial tub-

ing is customarily made. As above stated, the more common of these metals are attacked by ingredients of shaving creams, toothpastes, and similar preparations, and in order to protect the metal of the shell from contact with the contents of the container, the shell is provided with a lining of relatively thin flexible metal which is not affected by the cream or paste. Preferably this lining consists of a collapsible metal tube like those in which shaving cream, toothpaste, or the like, are commonly sold. Such tubes may be made of tin, or of other metals commonly used for this purpose. The body of such a tube is indicated in Fig. 3 at 6 and it is provided with the usual integral shouldered portion or head 7 and an externally threaded nozzle 8 to receive the cap 9. These tubes can readily be purchased from the manufacturers who supply the shaving cream and toothpaste manufacturers.

The preferred method of mounting the lining tube in the shell consists in inserting a mandrel in the tube 6, this mandrel fitting the interior of the tube closely. The tube with the mandrel in it is then placed in the shell 3, the shell and tube being of such dimensions that the latter fits snugly in the former. As above indicated, the shell is contracted at its upper end and the end piece 4 is provided with an aperture only very slightly larger in diameter than the external diameter of the nozzle 8 so that the nozzle can pass freely through said aperture. The upper end of the shell then is placed in a die and considerable pressure is applied to the mandrel to expand the metal of the tube between the head 7 and nozzle 8 and cause it to flow around the edge of the opening in the end piece 4 and lock itself to the shell, as clearly shown in Fig. 3. The mandrel next is withdrawn and the part of the tube 6 which is left extending from the shell 3 is bent over the lower edge of the shell and is crimped upwardly around said end and into a groove 10, Fig. 3, of reduced diameter which is formed in the shell. A ring or ferrule 12 then is slipped on to the crimped over portion of the lining and has either a shrunk or forced fit with this part of the container so that it securely holds the lower end of the lining in place. The lining thus is secured permanently to the shell at both its top and bottom.

In order to expel the contents of the tube through the nozzle 8 the container is provided with a plunger 13 which fits slidably inside the lining 6. By removing the cap 9 and forcing the plunger 13 upwardly, any desired proportion of the contents of the container can be discharged. The plunger should be made of tin or some other

metal which is not affected by the shaving cream, toothpaste, or the like.

When the plunger has substantially reached the upper limit of its movement and the container consequently has been substantially emptied of material, it then becomes necessary to withdraw the plunger to permit the refilling of the shell. This is conveniently accomplished by providing the plunger with a stud 14 externally threaded to fit the internally threaded end of the 10 razor handle 1. The handle is screwed on to the stud as shown in Fig. 4, and the stud may be then withdrawn from the shell, after which the container may be filled and the plunger replaced.

It will thus be evident that the invention provides a permanent container for shaving cream, toothpaste, and the like, which can be used without fear of the material becoming contaminated by its contact with the metal of the container, which is convenient to use, and which can be manufactured very economically. It is contemplated that the plunger shown can be used in containers made by other methods.

While we have herein shown and described a preferred embodiment of our invention, it will be evident that the invention may be embodied in other forms without departing from the spirit or scope thereof.

Having thus described our invention, what we desire to claim as new is:

1. A container of the character described, com-

prising a rigid tubular metal shell, a flexible metal tube lining said shell and having a discharge nozzle at one end thereof fastened to the shell, a cap removably supported on said nozzle for closing it and means for permanently securing the opposite end portion of said tube to the shell.

2. A container of the character described comprising a rigid tubular metal shell, a flexible metal tube lining said shell and having a head fastened to one end of the shell and a discharge nozzle projecting from said head, a cap removably supported on said nozzle for closing it the opposite end of said tube being crimped around the end of said shell and secured thereto.

3. A container of the character described comprising a rigid tubular shell, a metal tube forming a lining for said shell and having a discharge nozzle at one end thereof fastened to said shell, means for securing the opposite end portion of said lining tube permanently to said shell, a cap for closing the end of said nozzle, and a plunger slideable inside the lining for said shell and operable to expel the contents of the container through said nozzle, said plunger having a screw threaded stud projecting from the side thereof opposite to said nozzle to receive an implement for withdrawing the plunger from the shell.
